UNITED STATES PATENT OFFICE.

AUGUSTO SANDINO Y BARCON, OF CORUNNA, SPAIN.

BOILER-FEEDER.

SPECIFICATION forming part of Letters Patent No. 501,315, dated July 11, 1893.

Application filed December 4, 1891. Serial No. 414,050. (No model.)

To all whom it may concern:

Be it known that I, AUGUSTO SANDINO Y BARCON, of Corunna, Spain, have invented a new and Improved Boiler-Feeder, of which 5 the following is a full, clear, and exact description.

The object of the invention is to provide a new and improved boiler feeder, which is simple and durable in construction, automatic in 10 operation, and arranged to measure and register the quantity of water to be converted into steam.

The invention consists of certain parts and details and combinations of the same, as will 15 be fully described hereinafter and then pointed out in the claims.

Reference is to be had to the accompanying drawings, forming a part of this specification, in which similar letters of reference indicate 20 corresponding parts in all the figures.

Figure 1 is a sectional side elevation of the improvement as applied. Fig. 2 is an enlarged transverse section of the filling receptacle. Fig. 3 is an enlarged sectional side elevation of the valve for connecting the filling receptacle with the tank. Fig. 4 is a sectional plan view of the same, partly broken away. Fig. 5 is a transverse section of the inlet and outlet valves for the regulator, the 25 latter being shown in elevation. Figs. 6, 7, and 8 are enlarged cross sections of the regulator discharge valves on the lines 6—6, 7—7, and 8—8 respectively, of Fig. 5. Fig. 9 is an enlarged sectional side elevation of the regulator. Fig. 10 is a sectional plan view of the 30 same. Fig. 11 is a transverse section of the same on the line 11—11 Fig. 10; and Fig. 12 is a like view of the same on the line 12—12 Fig. 9.

40 The improved boiler feeder is provided with a filling receptacle A, adapted to contain the water to be discharged into the boiler. The bottom of the receptacle A is connected by a pipe B, with the water compartment of the boiler C and is provided with a valve D to connect or disconnect the said receptacle with or from the boiler whenever desired.

45 Into the receptacle A, extends, to within a short distance from the bottom, the pipe E, containing in its lower end a valve E', and extending upward through the top of the receptacle A, to connect with the reservoir or tank

F, for supplying the receptacle A, at intervals, with water for charging the boiler. The upper end of the receptacle A, is also connected 55 by a pipe G, containing a valve G', with a regulator H, provided with a steam inlet pipe I, containing a cock or valve I' and extending into the steam compartment of the boiler C. The pipe I is arranged in line with the 60 normal maximum level of the water in the said boiler C, so that steam can pass from the boiler into the regulator H, from the latter through the pipe G, past the valve G', into the receptacle A, to cause the water therein 65 to flow through the pipe B, into the boiler, as hereinafter more fully described.

In the receptacle A, is arranged a float J, carrying an upwardly extending rack J', in mesh with a gear wheel K', forming part of a 70 registering mechanism K, of any approved construction, and arranged in such a manner that the movement of the float J, registers the quantity of water discharged into the boiler from the said receptacle A. The top of the 75 float J, is adapted to engage a lever L', pivoted in the upper end of the receptacle A, and supporting a valve L, adapted to open and close the lower end of a pipe N, connecting the receptacle A with the tank F, as shown. 80 The under side of the float J, is adapted to engage and operate a lever or arm O connected by the rods O' and O², with a lever O³, supporting a valve O⁴ adapted to open and close a whistle O⁵, for sounding an alarm in 85 case the water in the receptacle A, falls to an extremely low and dangerous level.

The regulator H contains, in its bottom, a spring pressed valve P, leading to a gradually increasing outlet P', controlled by a valve 90 P², held on a screw rod P³, for adjusting the said valve to regulate the quantity of water passing through the outlet P', during a certain time, see Figs. 5, 6, 7 and 8. The water discharged through the outlet P', passes to a 95 receptacle Q, connected by a pipe Q' with the tank F, so that the water in the said receptacle Q, is forced back to the tank F by the pressure of steam coming through an extension G² of the pipe G, leading from the regulator H to the top of the said receptacle A, as above described.

In the lower part of the casing of the regulator H is arranged loosely a float R, carrying

a hollow stem R', engaging by a pin a segmental slot S' in a sector shaped weighted arm S secured on a shaft T, extending transversely and mounted to turn on centers held 5 in the casing of the regulator H, as plainly illustrated in Figs. 10, 11 and 12. On the weighted arm S are arranged lugs S² and S³ adapted to engage alternately opposite sides 10 of a projection T' formed on the rear face of a weighted arm T³ mounted to turn loosely on the shaft T. On this arm T³ opposite the projection T' and above shaft T is pivoted the valve U fitted to slide in suitable bearings in the regulator casing. The valve U is arranged 15 in line with the pipe I, and its outer free end is adapted to close or open the mouth of the said pipe I, so that the steam supply for the regulator can be shut off at the time the valve U is seated on the end of the said pipe I. 20 The latter is provided outside of the regulator H with the valve I' for permanently shutting off steam from the regulator whenever desired.

On the rear face of the weighted arm T³ is 25 arranged a lug T² adapted to be engaged by a hook U', formed on a spring pressed lever U² pivoted in the casing. On the front face of the arm T³ are arranged two lugs T⁴ and T⁵ between which passes the valve stem of 30 the valve U, and which serve to limit the up and down swinging motion of the arm T³.

On the front face of the arm S is arranged a short pin S⁴ adapted to engage a curved projection on the lever U² so that when the arm 35 S swings to the right, the said pin S⁴ comes in contact with and presses on the said curved projection to swing the lever U² outward out of engagement with the lug T² to free the arm T³ and to permit the latter to swing down- 40 ward as hereinafter more fully described.

The operation is as follows:—After a certain quantity of water has been injected into the boiler, the valves L, E' and P, are held on their seats by the pressure of steam passing through 45 the pipe I into the regulator H, and passing from the latter through the pipe G into the receptacle A. The valves D and G' and the valve U, are held open, the latter by the action of the weighted arm S, the valve D by 50 the pressure of the water in the receptacle A, and the valve G' by the pressure of the steam passing through the pipe G from the regulator H into the receptacle A. The float J, is at this time descending, and the first wheel K' 55 of the registering apparatus K, is disengaged from the indicating wheels. The float R is then in its lowermost position. When a feeding or injection is being finished the steam enters freely into the regulator H and the receptacle A, the different parts then being in 60 the position shown in the drawings. A moment later the water in the boiler will reach the mouth of the valve tube I and will enter the same and pass into the casing of the regulator H, not only on account of the rise of 65 the level in the boiler, but more particularly on account of the reduction of pressure pro-

duced in the said regulator H and receptacle A as soon as the steam is prevented from passing from the boiler to take the place of that which is constantly condensed in the said regulator and receptacle. When the water from the boiler enters the regulator H the float R therein begins to be submerged and consequently acquires an ascending force, and when this is sufficient to counterbalance the weight of the arm S and the friction of the working parts connected therewith, it will begin to rise, causing the said arm S to describe an angle of sixty degrees. At this time the center of gravity of the arm S will pass to the other side of the vertical line which passes through the center of the shaft T, and the said arm will fall suddenly to the opposite side, the segmental slot S' permitting such movement, which extends through an angle of 75 sixty degrees. Before this movement of the arm S, however, is finished, the lug S³ has moved the hook U' toward the outside and the weighted arm T³ can fall freely, and as it carries the valve U with it, the latter will close the mouth of the pipe I as the weighted arm T³ is so calculated that its force will be equal to the force of the steam at its maximum pressure on the valve U. As the arm S has 80 moved sixty degrees + sixty degrees, that is one hundred and twenty degrees, and as the space left by the two lugs S² and S³ is not more than about one hundred and five degrees, it is clear that as the lug S² rests on the projection 85 T' it causes the latter to move fifteen degrees, which is necessary so that the valve U may reach its seat and be held thereon. In this way communication with the boiler and regulator H is cut off. The reduction of pressure 90 which constantly takes place in the regulator H and the receptacle A, as already described, produces a retrogression in the water which passes from the receptacle A to the boiler C by means of the tube B, and this retrogression closes the valve D automatically. Thus, we have the apparatus entirely cut off 95 from the boiler, the apparatus still containing some water and steam at nearly the same pressure as that in the boiler. The pressure 100 of this steam diminishes progressively because it has lost heat by radiation, and a time will come in which this pressure will be overcome in the discharge valve L by the weight 105 of the lever L'. Then all the steam and the air contained in the apparatus will escape by 110 the said valve and tube into the atmosphere and then the weight of the water in the tank F will open the valve E' and the receptacle A 115 will begin to fill. In consequence of this the float J will rise and its rack will actuate the recording apparatus K so as to record the amount of water which enters the receptacle 120 A. But as part of this water passes out later from the regulator H by means of the tube 125 P', the end of the lever L' is so arranged that it will move down sufficiently to prevent the rise of the float J before a volume of water 130 equal to that which afterward passes out at

the tube P enters the receptacle A. In this manner the recording apparatus K is also stopped and its first wheel K' is thrown out of mesh with the others when the float moves 5 down so that the result is that only the volume of water which is injected into the boiler and which is to be converted into steam therein will be recorded. The receptacle A is now filled with water from the tank F, the float J 10 is at its highest point, and the lever L' rises and closes the valve L so that the receptacle A remains filled with water with all its valves closed and at rest. In the meantime the several devices in the regulator H are at work in 15 the following manner: From the moment when the discharge valve L was opened and atmospheric pressure was thereby established in the interior of the apparatus, the spring for the valve P caused the latter to open, and 20 as the rod P² had previously been placed by the operator in the proper position to leave a certain sized outlet in the tube P', the water from the regulator H will run out through the tube P and accumulate in the exhauster Q, or 25 is allowed to run off as desired. The time for the duration of this discharge of the water from the regulator H is so regulated that the level of the water in the boiler will not fall more than necessary. The outflow of the 30 water from the regulator H causes the emer- 35 sion of the float R which will pull more and more on the arm S and finally a time will come when this pull will be sufficient to draw the arm S to the right and cause it to describe an angle of sixty degrees, so that its center of gravity will finally pass to the right of the vertical line and then the arm will fall suddenly to this side, thereby describing another sixty degrees permitted by the segmental slot 40 S'. From the time that the arm S began to move the valve U remained fixed on its seat, held there only by the weight of the arm T³ which is sufficient for the purpose. The pin 45 S³ finally leaves the hook O' so as to be free to be acted on by its spring, and finally while describing the last fifteen degrees, the corresponding lug S² abuts on the projection T' and thereby causes the arm T³ to turn so that the valve U is forced open. At this move- 50 ment the steam from the boiler will pass to the regulator and fill it and at the same time close the valve P and press the valves E' and L firmly against their seats. The pressure in the apparatus and that in the boiler thus 55 becomes equalized and the water from the receptacle A will run by gravity from the receptacle to the boiler, automatically opening in its discharge the valve D and filling the said boiler up to the entrance of the tube I, 60 at which time the water will pass through the tube I into the regulator H to act on the several parts therein, as above described. As the operator can regulate the time that the condensations of steam in the apparatus will 65 last, as this will always be less the greater the weight of the lever L' is, and as the operator can also regulate the time that the dis- charge of the water through the tube P' will consume—which time is always the same between two successive injections—the apparatus can be so set that during the ordinary operation of the device the float J will not fall to the bottom of the receptacle A. But if on account of a great waste of steam or the escape of water, the water in the boiler should fall more than has been provided for, then the receptacle A will be completely emptied and the whole weight of the float J will bear on the lever O, so that the valve O⁴ will, without fail, open, whereby the alarm whistle is sounded, thus warning the engineer he can now re-establish the normal condition. This is easily done, as for this purpose the operator closes the valve I' by hand and opens the tube P' wide, and by means of the weighted lever 85 shown in Fig. 3, opens the discharge valve L. In this manner the time for the condensation of the steam is reduced to an instant, and the outflow of water by the tube P' to considerable less time. In this short time the receptacle A has filled and now on opening the valve I', the steam will cause a new injection of water in the manner above described. A repetition of the preceding operation by the operator will be sufficient to feed the boiler. 90 When the alarm is produced by a change of consumption of the water in the boiler, then it is only necessary to regulate the outflow of the water in the tube P' after the level of the water in the boiler has been re-established, 95 so that all continues in the normal way above described.

Having thus described my invention, I claim as new and desire to secure by Letters Patent—

1. In a boiler feeder, a regulator, a pipe connecting the same with the boiler at the line of maximum normal level of water, a float located within said regulator and adapted to be raised by the water entering the regulator from the boiler through the said pipe when the water in the boiler has attained its maximum normal level, a valve adapted to be operated by the upward movement of the said float so as to interrupt the connection between the regulator and the boiler, a filling receptacle adapted to contain water to feed the boiler, pipes connecting the said filling receptacle to the boiler and to the regulator respectively, and valves in said pipes, these valves being adapted to be automatically closed by the reduction of pressure in the filling receptacle and in the regulator when the admission of steam to the latter ceases, substantially as described.

2. In a boiler feeder, the combination with a regulator and a pipe connecting the same with the boiler at the line of maximum normal level of water, of a valve held in the said regulator and adapted to close the connection of the casing and the boiler, a weighted arm for moving said valve, a segmental arm for actuating the said weighted arm and a float connected with the said segmental arm in such

a manner as to permit the segmental arm to drop of its own accord after the arm has passed a vertical position, the said float being adapted to be raised by the water entering the regulator from the boiler when the water in the latter has attained its maximum normal level, substantially as described.

3. In a boiler feeder, a filling receptacle provided with an air escape valve adapted to be closed by the action of a float kept closed by the pressure of the steam in the receptacle opened by its weight when the pressure in the receptacle decreases to a predetermined limit, in combination with a tube, an upper feeding tank connected by the said tube with the said receptacle, and a valve arranged on the lower end of the said tube and adapted to open by the pressure of the water in the said tank after the said escape valve opens, the said tube valve being adapted to be closed by the pressure of the steam which enters the said receptacle from the boiler, substantially as shown and described.

4. In a boiler feeder, the combination with a regulator, a pipe connecting the same with the boiler at the line of maximum normal level of water, a float located within said regulator and adapted to be raised by the water entering the regulator from the boiler through the said pipe when the water in the boiler has attained its maximum normal level, a valve adapted to be operated by the upward movement of the said float so as to interrupt the connection between the regulator and the boiler, a filling receptacle adapted to contain water to feed the boiler, a supply tank connected to the filling receptacle by a pipe, a valve in said pipe adapted to be closed by the pressure of steam in the filling receptacle, pipes connecting the latter to the boiler, and to the regulator respectively, and valves in said pipes, these valves being adapted to be automatically closed by the reduction of pressure in the filling receptacle and in the regulator when the admission of steam to the latter ceases, substantially as described.

5. In a boiler feeder, a filling receptacle provided with a tube leading to the boiler and a valve arranged on the said tube and held to its seat by the pressure of the steam in the boiler, in combination with an air escape valve arranged on the said filling receptacle and adapted to be closed by the pressure of the steam in the said filling receptacle, a tank located above the said filling receptacle, a tube leading from the said tank to the said filling receptacle and provided at its lower end with a valve adapted to be opened by the pressure of the water in the said tank after the said air escape valve is opened, and a float arranged in the said filling receptacle to rise with the water that flows from the said tank to the said filling receptacle, the said float being provided with a rack for controlling a registering apparatus for registering the water which flows from the tank, the said float being retained in an uppermost position

by the lever of the said escape valve after the latter has closed and at a time when the volume of water which is yet to enter the filling receptacle is equal to that which afterward passes out by the regulator, so that only the quantity of water which is to be converted into steam is registered by the registering apparatus, substantially as shown and described.

6. In a boiler feeder, a filling receptacle having a valved pipe leading to the atmosphere and provided with a weighted escape valve held on its seat by the pressure within the receptacle so that a reduction of the pressure within the receptacle causes a closing of the valve in the pipe leading to the boiler, an opening of the said escape valve, and a tank located above the said filling receptacle and connected with the latter by a pipe having at its inlet end a valve adapted to open by the pressure of the water from the said tank after the said escape valve has opened, substantially as described.

7. In a boiler feeder, a filling receptacle having a valved pipe leading to the boiler and provided with a weighted escape valve held on its seat by the pressure within the receptacle so that a reduction of the pressure within the receptacle causes a closing of the valve in the pipe leading to the boiler, an opening of the said escape valve, a tank located above the said filling receptacle and connected with the latter by a pipe having at its inlet end a valve adapted to open by the pressure of the water from the said tank after the said escape valve has opened, and a float arranged in the said filling receptacle and adapted to rise by the water flowing from the tank to the said receptacle, the said float being arranged to seat the escape valve when reaching its uppermost position, substantially as described.

8. In a boiler feeder, the combination with a regulator having a graduated outlet and a float controlled valve adapted to connect the boiler with the said regulator to admit steam into the latter, of a filling receptacle connected with the said regulator and with a water supply, and a pipe leading from the said receptacle to the boiler and provided with a valve held on its seat by the pressure from the boiler, but opening as soon as the said regulator valve opens and admit steam to the said filling receptacle, substantially as described.

9. In a boiler feeder, the combination, with a filling receptacle provided with a supply pipe containing a valve, a regulator connected with the boiler, and a steam pipe containing a valve and connecting the said regulator with the said filling receptacle, of a valve held in the said regulator and adapted to open and close the pipe connecting the regulator with the boiler, a float held in the said regulator and controlling the said valve, an outlet provided with a self-opening valve to permit the water of condensation and the water which entered from the boiler by the connecting

pipe to discharge from the said regulator, and an adjustable valve held in the said outlet to regulate the time necessary to discharge the water of condensation from the said regulator, substantially as shown and described.

10. In a boiler feeder, the combination with a regulator having an outlet tube governed by a rod to regulate the quantity of water which passes through the said tube, and a float for governing a valve connecting the boiler with and disconnecting it from the said regulator in order to admit or cut off the entrance of the steam to the regulator, of a filling receptacle connected with the said regulator and with a water tank, and a tube which leads to the boiler from the said receptacle and is provided with a valve held to its seat

by the pressure from the boiler, the said valve being adapted to open as soon as the said valve of the regulator opens and admits steam to the apparatus, substantially as shown and described.

11. In a boiler feeder, a regulator having a float provided with a hollow rod through which steam can enter the said rod extending nearly to the bottom of the float, the walls of the said float being subjected to equal pressure on the inside and outside, substantially as shown and described.

AUGUSTO SANDINO Y BARCON.
